UNITED STATES PATENT OFFICE

HENRY S. MEARS, OF PORTLAND, OREGON, ASSIGNOR TO INTERNATIONAL HARVESTER COMPANY, A CORPORATION OF NEW JERSEY

FORMER FOR COMBINATION FIBER PAPER TWINE

Application filed November 29, 1929. Serial No. 410,413.

This invention relates to mechanism adapted for use in the manufacture of combination paper and fiber twine. More particularly, the invention relates to improvements in a forming device, or so-called frog, for such mechanism of the type illustrated in the United State patent to Rice 1,320,922 of Nov. 4, 1919.

Paper covered fiber twine must withstand severe treatment, and accordingly it is highly important that the elements thereof, to-wit, the twine fiber and the paper cover, be securely interlocked and intertwined.

Accordingly, it is the primary object of this invention to improve the former or frog which places the paper around the fiber; to provide means associated with such a forming device to prevent the paper from running out laterally in between the cover and the base of this former when the twine is being formed; to provide such means, which additionally functions to engage and deflect the edges of the paper strip as it goes into the frog to turn the same under, thus making a better crimp and consequently a more perfect twine.

Other objects of this invention should be apparent to those skilled in this art as the disclosure is made.

Briefly, these desirable objects are achieved in a frog of the type disclosed in the patent above mentioned, which frog or former embodies a base and a hinged upper section or cover connected thereto, there being complementary fiber distributing and paper spreading surfaces between the two parts to cause the paper to be spread around and crimped interlockingly with the fiber to form the twine.

The improvements of this invention particularly comprise abutment means at opposite sides of the spreading and distributing means, which abutment means is contacted by the moving strip of paper, thereby causing the edges of said paper strip better to be deflected downwardly and turned inwardly relative to the fiber.

An illustrative form of the invention is shown in the accompanying sheet of drawings, in which:

Figure 1 is a side elevational view, partly

in section, showing the general organization of the machine for making the combination fiber paper twine;

Figure 2 is a longitudinal, central sectional view through the former or frog;

Figure 3 is a cross sectional view through the frog as seen along the line 3—3 appearing in Figure 2, when viewed in the direction of the arrows shown;

Figure 4 is a top plan view of the base or lower section with the cover or upper section removed;

Figure 5 is a detail cross sectional view through the cover, as seen along the line 5—5 appearing in Figure 2 when viewed in the direction of the arrows; and,

Figure 6 is a bottom plan view of the cover or upper section detached from the base.

The feeding mechanism for the paper ribbon and the fiber sliver is the same as that shown in the patent above mentioned, and consists of a large feeding roller 10 mounted above and adapted to contact with two smaller feeding rollers 11 and 12, said last two mentioned rollers designed to be positively driven through the intermediary of any appropriate driving mechanism. These rollers may be supported in any suitable manner, the roller 10 preferably being journaled in a slidably journaled box and having suitable weighting devices for pressing it in contact with the rollers 11 and 12.

The fiber in the form of a sliver is fed to the feeding rollers by the usual gill bars 13 and gill pins 14 in a manner well known in this art. The ribbon of paper 15 is drawn by the feeding rollers from a suitable source of supply, such as a roll, and before reaching the feeding rollers, passes under an idler wheel 16.

The feeding rollers 10, 11 and 12 positively draw the paper and the fiber sliver forwardly and feed them to the former or frog 17, which is suitably mounted on the frame of the machine in advance of the feeding rollers, as shown. In the present instance the frog 17 comprises two main sections, to-wit, a stationary base or lower section 18 and a hinged cover or upper section 19, which is pivotally mounted on a pin 20 carried by upwardly ex-

tending lugs 21 secured to or formed as a part of the stationary section 18. The exterior surface of the frog or former is conical in shape and a lug 22 extends upwardly from the hinged section 19 which provides a convenient hand hold to be utilized in lifting the hinged section. The hinged section may be held securely in place on the stationary section by any appropriate form of latching mechanism 23, as shown and described in the prior patent mentioned. Accordingly, this latching mechanism will not be described in detail.

The interior of the hinged cover section 19 is cut away or hollowed out, as shown in the cross sectional views in Figures 3 and 5, the interior wall conforming in shape to a half of a hollow cone. The stationary base section 18 is provided at its rear end with a 20 cave portion that receives an insert frog member 24 having a concave surface 25 at its back end, from which rises a convexed, central ridge 26 having an upper, straight horizontal edge, as shown in Figure 2, terminating at its 25 front in a pointed end 27, while the rear end of this ridge curves down and slopes to a rear point 28. Between the lower section 18 and the frog insert piece 24, and on each side of the convex, enlarged part 26, is a groove 29 30 semi-circular in cross section, of the kind shown in the previous patent mentioned. The back end of the frog insert 24 has flanges 30 bent out laterally to engage the members 21 of the lower section or base 18, and a screw 31 is provided securely to hold the frog insert in position in the base 18.

The paper enters the former above the fiber, as shown in Figure 1, and comes into contact with and is guided by the inner wall 40 of the hinged section and is thereby transversely curved, as shown in Figure 3, and in the prior patent. The portion of the fiber not already in contact with the paper, due to the pressing and creasing operating of the 45 roller 10 as it enters the frog, is guided by the concave rear portion 25, and, as it reaches the convex portion of the ridged part 26, is distributed transversely, or spread across the width of the paper which is disposed above 50 it. The fiber and paper are held in contact with the convex surface 26 by the upper hinged section of the former.

For the purpose of better interlocking the paper cover with the sliver, abutments are 55 provided on opposite sides of the fiber distributing and paper spreading surfaces inside of the frog. Accordingly, the cover section 19 has securely fitted thereinto two depending abutments in the form of pins 32, which are adapted, when the cover is down, to seat in recesses 33 disposed one each in the grooves 29. It is to be noted that the inner surface of these pins are recessed as at 34 to 60 form an arcuated surface. Accordingly, when the edge of the paper strip is contacted

by the inner surfaces of these pins, the edges of said strip are caused to be deflected and forced downwardly and inwardly with respect to the sliver, thereby insuring that a better crimping of the paper will result with 70 respect to the fiber. Further, these pins prevent lateral running of the paper outwardly between the sections, which would, of course, be highly objectionable.

As stated in the previous patent, the pressure of the roller 10 on the paper ribbon forces the ribbon against the loose fibers and thereby produces longitudinal creases in the paper. As the paper approaches the forward end of the frog, the side edges of the paper have 80 been curled, since the conical shape of the former and the action of the pins 32 cause the paper to assume a smaller space as it approaches the front end of the frog. The turned down edges of the paper, therefore, 85 are forced into the grooves 29, as shown in Figure 3, disposed at the sides of the convex portion 26. As the paper reaches the front end of the former, the inwardly curved edges are further curved in an obvious manner, because the convex surface 26 draws out into a point 27.

After leaving the frog, the paper passes through a crusher 35 and a nipper 36, and thence to a suitable spinning mechanism.

From this disclosure it will now be appreciated that the deflecting action of the abutments 32 materially enhances the operation of turning and deflecting the edges of the paper, which obviously must result in a better covering of the paper with respect to the fiber sliver.

While there has been shown but one embodiment of the invention in the above specification, it should be understood that the 105 same is capable of modifications and that modifications may be employed without departing from the spirit and scope of the invention as expressed in the following claims.

What is claimed is:

1. A former for fiber paper twine machines, said former comprising upper and lower sections, cooperating paper and fiber guiding and distributing surfaces on adjoining faces of the sections, and abutments at opposite sides of said surfaces for causing the edges of the paper to be tucked under the fiber, said abutments augmenting the tucking action of said surfaces and preventing the paper from running out laterally of the sections.

2. A former for fiber paper twine machines, said former comprising upper and lower sections, cooperating paper and fiber guiding and distributing surfaces on adjoining faces of the sections, and vertical pins at opposite sides of said surfaces for causing the edges of the paper to be tucked under the fiber.

3. A former for fiber paper twine machines, said former comprising upper and

lower sections, cooperating paper and fiber guiding and distributing surfaces on adjoining faces of the sections, and vertical pins at opposite sides of said surfaces for causing the edges of the paper to be tucked under the fiber, said pins having their inner edges arcuated.

5 4. A former for fiber paper twine machines, said former comprising a lower section, including fiber distributing means, an upper section pivotally connected to the lower section and including paper spreading means, and an abutment on each side of the distributing and spreading means for turning the edges of the paper downwardly and inwardly, said abutments augmenting the tucking action of the surfaces and preventing the lateral running out of the paper between the sections.

10 5. A former for fiber paper twine machines, said former comprising a lower section, including fiber distributing means, an upper section pivotally connected to the lower section and including paper spreading means, 25 and a pin carried by one of the sections on each side of the distributing and spreading means for turning the edges of the paper downwardly and inwardly, said pins adapted to fit into recesses in the other section.

30 6. A former for fiber paper twine machines, said former comprising a lower section, including fiber distributing means, an upper section pivotally connected to the lower section and including paper spreading means, 35 and vertically disposed pins carried by one of the sections on each side of the distributing and spreading means for turning the edges of the paper downwardly and inwardly, said pins having their inner faces 40 recessed to form guide surfaces.

In testimony whereof I affix my signature.
HENRY. S. MEARS.
